CLAIM

The ornamental design for a water bath-dryer combination for histological preparation as shown and described.

DESCRIPTION

FIG. 1 is a left-top-front perspective view of a first embodiment of a water bath-dryer combination for histological preparation, showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a left-top-front perspective view of a second embodiment of a water bath-dryer combination for histological preparation;

FIG. 9 is a front elevation view thereof;

FIG. 10 is a rear elevation view thereof;

FIG. 11 is a right side elevation view thereof;

FIG. 12 is a left side elevation view thereof;

FIG. 13 is a top plan view thereof;

FIG. 14 is a bottom plan view thereof;

FIG. 15 is a left-top-front perspective view of a third embodiment of a water bath-dryer combination for histological preparation;

FIG. 16 is a front elevation view thereof;

FIG. 17 is a rear elevation view thereof;

FIG. 18 is a right side elevation view thereof;

FIG. 19 is a left side elevation view thereof;

FIG. 20 is a top plan view thereof; and,

FIG. 21 is a bottom plan view thereof.

Broken lines are included for purpose of illustrating portions of the water bath-dryer combination for histological preparation that form no part of the claimed design.
